UNITED STATES PATENT OFFICE.

EDWARD E. HINRICHSEN, OF NEW YORK, N. Y., ASSIGNOR, BY MESNE ASSIGNMENTS,
TO WESTERN ELECTRIC COMPANY, INCORPORATED, A CORPORATION OF NEW YORK.

TELEPHONE-EXCHANGE SYSTEM.

1,235,688.

Specification of Letters Patent. Patented Aug. 7, 1917.

Application filed June 8, 1915. Serial No. 32,841.

To all whom it may concern:

Be it known that I, EDWARD E. HINRICHSEN, a citizen of the United States, residing at New York, in the county of New York and State of New York, have invented certain new and useful Improvements in Telephone-Exchange Systems, of which the following is a full, clear, concise, and exact description.

- 10 This invention relates to telephone exchange systems, and more particularly to telephone systems of the class in which the subscriber's line is available for toll connections at all times.
- 15 It is the object of this invention to provide means whereby toll calls may be given precedence over all other calls, even when a subscriber's line wanted for a long distance call happens to be in use on a local connection.
- 20 In accordance with this invention means are provided whereby an answering or A operator is given a peremptory disconnect signal in the event the called subscriber for a toll connection is already engaged in con-
- 25 versation. This means comprises an auxiliary or special connecting circuit located at a switching operator's position, said circuit including means which effect the operation of a signaling device, such as the flashing
- 30 of a line supervisory lamp, forming a part of the A operator's cord circuit associated with said subscriber's line. When the A operator observes the flashing of the subscriber's supervisory lamp, it will be a signal for her to take down the connection then existing with the wanted subscriber's line, thus rendering said line available for toll purposes.

40 Special features of the switching operator's connecting circuit contemplated by this invention will be apparent upon a reading of the specification.

The accompanying drawing illustrates diagrammatically one embodiment of this 45 invention.

A subscriber's substation 1 is connected by means of line wires 2, 3 to multiple jacks 4 at a central office. Associated with the line circuit is the usual line relay 5, which controls a line lamp 6 and a cut-off relay 7. A portion of an A operator's cord circuit is shown which includes only the equipment necessary to illustrate this invention, said

equipment comprising an answering plug 8 having the tip and ring strands thereof connected to repeating coil windings in the usual manner. Included in the ring strand is a supervisory relay 9 which controls the circuit of a supervisory lamp 10. Likewise only the portion necessary to illustrate this invention is shown of a B or switching operator's cord circuit. The auxiliary or special connecting circuit which is the feature of this invention terminates at one of its ends in a jack 14 and at the other in a plug 16. This circuit is preferably located at the switch-board of the B or switching operator.

In describing the operation of the apparatus illustrated in the drawing, we will assume that the substation 1 is connected to another substation by the A operator's cord circuit, and that a toll operator has received a call for substation 1. The switching or B operator having made the usual busy test to 75 determine whether the substation 1 is in use and finding it busy, inserts the calling plug 13 of a switching trunk circuit into the jack 14 of the auxiliary circuit. Having done this she next operates a listening key 73 and inserts the calling plug 16 of this circuit into one of the multiple jacks 4. By these acts on the part of the operator several circuits are established, one of which is a circuit for effecting the operation of the relay 15, which may be traced as follows: battery 17, transformer 18, resistance 19, conductor 20, lower winding of the relay 15, conductor 21, winding of relay 22, conductor 23, contact 24, conductor 25, sleeve side of the plug 16 and jack 4 respectively, conductor 26, coil of relay 7, to ground. The circuit just described energizes the relay 22, which in pulling up its armature closes contact 31, thus completing a circuit through the windings of relay 15, which may be traced as follows: battery 17, transformer 18, resistance 19, conductor 20, upper and lower windings of relay 15, conductor 32, contact 31, to ground. It may be mentioned here that the relay 15 is differentially wound, and the upper winding is so proportioned to the lower winding that in certain instances when both windings are energized the upper one neutralizes the lower one and the relay remains inactive, 100 as is the case when the plug 16 is inserted

into a multiple jack of a line not in use. At other times, as for example, when a plug of a cord or trunk circuit is inserted into another of the multiple jacks, either before or 5 after the insertion of the plug 16, the currents through the windings of the relay 15 are so changed by changing the resistance of the circuit including said relay, that it operates. Controlling the operation of a differentially wound relay by varying the 10 amount of resistance in its energizing circuit, by either shunting a part thereof or adding more, is an old expedient and well understood in the art.

15 The operation of the relay 15 closes a circuit through the lower winding of the relay 33 which may be traced as follows: battery 34, lower winding of relay 33, conductor 35, contact 36 of relay 15, to ground. The energization of the relay 33 opens contact 37 and closes contact 38, but the closure of this contact has no effect at this time as the contact 49 is open. The B operator may now 20 converse with the subscriber at substation 1, and having informed said subscriber that he is wanted on a toll connection the operator restores the listening key 73. Upon the restoration of the listening key 73, the upper winding of the relay 33 is bridged across the 25 tip and ring strand of the A operator's cord circuit which maintains the supervisory relay 9 energized over a circuit which may be described as follows: battery 11, winding of supervisory relay 9, ring side of the plug 8 and jack 4, over line wire 3 to the multiple 30 jack in which the plug 16 has been inserted, through the ring side of the plug 16, contact 39, conductor 40, contact 41, conductor 42, upper winding of the relay 33, conductor 43, contact 44, conductor 45, contact 46, tip side 35 of the plug 16 and jack 4, line wire 2, back to the tip side of the answering jack 4 and plug 8, to ground. The bridging of the upper winding of the relay 33 in this circuit 40 prevents the lighting of the supervisory lamp 10 by maintaining the relay 9 in an energized condition.

Simultaneously with the completion of the above traced circuit by the restoration of 45 the listening key 73, the following circuit is established through the relay 50: battery 34, contact 38, conductor 47, contact 49, conductor 48, coil of relay 50, to ground. The consequent operation of relay 50 establishes the following circuit through an interrupting device 51 which circuit may be described 50 as follows: battery 52, interrupter 51, conductor 53, contact 54, conductor 25, sleeve side of the plug 16 and jack 4, through the 55 sleeve side of multiple jack 4 containing plug 8, lamp 10, to battery 12. It will be noticed that the battery 52 is of opposite polarity to that of battery 12, and this difference in polarity increases the strength of the 60 current flowing over the above circuit so

that the lamp 10, normally extinguished, will be intermittently flashed by the interrupting device 51. The flashing of this lamp may be taken as a peremptory signal for the A operator to withdraw her answering 70 plug 8.

A busy tone is placed upon the ring strand of the jack 14 by the closure of contact 56 for the purpose of notifying the toll operator that the switching operator is attempting to make connection with the desired party. The circuit of this tone may be traced as follows: battery 57, coil or relay 58 (which would ordinarily be a supervisory relay), ring side of the plug 13 and 80 jack 14, contact 56, conductor 59, resistance 70, transformer 71, interrupter 72, to ground.

The A operator having observed the flashing of the supervisory lamp 10, withdraws the answering plug 8. The withdrawal of 85 this plug produces the deenergization of the relays 33 and 50. It may be stated here that a resistance 55 is inserted in a shunt around the interrupting device 51, so that the cut-off relay will be maintained energized during 90 the interval required for the relays 33 and 50 to restore to normal position upon the removal of the plug 8. This feature prevents the inadvertent flashing of the line lamp 6. The deenergization of the relay 33 closes a 95 circuit through the relay 60 which may be traced as follows: battery 34, contact 37, conductor 61, coil of relay 60, conductor 62, contact 63, conductors 64, 32, contact 31, to ground. The actuation of the relay 60 connects the subscriber's line through to the switching trunk of the switching operator by closing its front contacts 65 and 66. Circuit connections are now made from the toll operator's position through to the substation 100 1. 105

A busy tone is placed upon the sleeve of the multiple jack 4 associated with the subscriber's line for indicating the busy condition of this line to a second operator. The 110 circuit of this busy tone may be traced as follows: battery 17, transformer 18, resistance 19, conductor 20, lower winding of relay 15, conductor 21, winding of relay 22, conductor 23, contact 24, conductor 25, sleeve 115 side of plug 16 and jack 4 respectively, conductor 26, coil of relay 7, to ground. To provide against the possibility of the switching operator inadvertently leaving the plug 16 in the multiple jack 4 when the subscriber 120 at substation 1 has replaced his receiver upon the switchhook, the supervisory lamp 67 is provided. The circuit for this lamp is established over the following path: battery 17, transformer 18, resistance 68, lamp 67, contact 69, conductors 64, 32, contact 31, to ground. The switching operator observing the lamp 67 lighted, will know that she has failed to disconnect the plug 16 of the auxiliary circuit from the line of substation 1. 130

This feature will prevent a busy tone inadvertently being left upon the line of substitution 1.

- From the above it is apparent that by the 5 means provided in accordance with this invention, a toll operator will have command of a subscriber's line at all times, and in the event the toll operator wishes to make a connection with a line already in use, she may 10 connect with the line, inform the wanted party that he is wanted on long distance and then give the A operator a peremptory disconnect signal to take down the then existing connection with the wanted subscriber. 15 This feature is important in that it gives precedence under all circumstances to long distance calls; prevents the inconvenience of reestablishing toll connections up to the point of the wanted subscriber, and quite 20 often will save a toll call which would otherwise be lost in case the wanted subscriber's line is not available when the connection was first set up.

What is claimed is:

- 25 1. In a telephone system, a subscriber's line terminating in multiple line jacks at a central office, a link circuit and a switching operator's connecting circuit each adapted to be connected with said line, a source of 30 current and a line supervisory lamp connected therewith and included in said link circuit, a manually actuated switch associated with said connecting circuit, means associated with said connecting circuit and 35 controlled by said switch whereby the operator may notify a subscriber on a busy line regarding a waiting call, and automatic means associated with said connecting circuit and controlled by said switch for flashing 40 said supervisory lamp when said link circuit and said connecting circuit are simultaneously connected with said line.

2. In a telephone system, a subscriber's line terminating in multiple line jacks at a 45 central office, a link circuit and a switching operator's connecting circuit each adapted to be connected with said line, a source of current and a line supervisory lamp connected therewith included in said link circuit, manually and automatically operable 50 switching means included in said connecting circuit, and means for causing said supervisory lamp to be flashed when said circuits are simultaneously connected with said line, 55 said means being under the conjoint control of said switching means.

3. In a telephone system, a subscriber's line terminating in multiple line jacks at a central office, a link circuit and a switching operator's connecting circuit each adapted to be connected with said line, a source of 60 current and a line supervisory lamp connected therewith included in said link circuit, manually and automatically operable 65 switching means included in said connecting

circuit, said manual switching means controlling the operation of said automatic switching means, and means associated with said connecting circuit for causing said supervisory lamp to be flashed when said link circuit and said connecting circuit are simultaneously connected with said line, said means being under the conjoint control of 70 said switching means.

4. In a telephone system, a subscriber's line terminating in multiple line jacks at a central office, a link circuit adapted to be connected with said line, a source of current and a line supervisory lamp connected therewith included in said link circuit, a switching operator's connecting circuit terminating in a plug at one end thereof, a circuit interrupting device, switching means for including said interrupting device in a circuit with said supervisory lamp, and a source of 75 current of opposite polarity to that normally associated with said lamp, said source of current being adapted to be interrupted by said interrupting device, whereby said lamp is caused to be flashed when said link 80 circuit and said connecting circuit are simultaneously connected with said line.

5. In a telephone system, a plurality of subscribers' lines terminating in multiple line jacks at a central office, a link circuit for connecting any pair of said lines together, a switching operator's connecting circuit adapted to be included in a toll connection, means included in said connecting circuit for permitting a switching operator to make 95 100 connection with a busy line, a manually actuated listening key in said connecting circuit, and means associated with said connecting circuit and controlled by said listening key for giving a busy tone to a toll operator when said connecting circuit is connected with a busy line whereby the toll operator is informed that the switching operator is endeavoring to establish a toll connection with said busy line.

6. In a telephone system, a subscriber's line terminating in multiple jacks at a central office, a link circuit adapted to be connected with said line, a signaling device included in said link circuit, a plug associated 110 115 with said signaling device, a switching operator's connecting circuit adapted to be included in a toll connection, means included in said connecting circuit for permitting a switching operator to make connection with 120 said line when said plug of said link circuit is inserted in one of said jacks, means for giving peremptory disconnect signal through the operation of said signaling device, and means for automatically establishing a circuit over the talking conductors of said 125 switching circuit upon the removal of said plug from said line.

7. In a telephone system, a subscriber's line terminating in multiple jacks at a cen- 130

tral office, a link circuit adapted to be connected with said line, a source of current and a line supervisory lamp connected therewith included in said link circuit a switching operator's connecting circuit terminating in a plug at one end thereof, means associated with said connecting circuit for causing said supervisory lamp to be flashed when

the plug of said connecting circuit is inserted in the multiple jack of a busy line, 10 and means independent of said plug under the control of the switching operator for controlling said flashing means.

In witness whereof, I hereunto subscribe my name this 5th day of June, A. D. 1915. 15
EDWARD E. HINRICHSEN.
